UNITED STATES PATENT OFFICE

DARRELL F. WOLF, OF PUNXSUTAWNEY, PENNSYLVANIA

WINDOW WASHER

Application filed April 9, 1931. Serial No. 527,311.

This invention relates to a window washing machine and it aims to provide a novel construction whereby a window while in a substantially closed position may be washed on the outside by the operation of mechanism from the inside of a building.

It is further aimed to provide a novel construction attachable to a window sash and in which the operating parts are rotatably and slidably mounted.

Another object is to provide a novel construction in which the brush or washing element will be moved over every part of a window pane incidental to operation and in which tension on the brush may be varied or adjusted.

The invention also includes a novel driving and operating means.

The more specific objects and advantages will become apparent from a consideration of the description following taken in connection with accompanying drawings illustrating an operative embodiment.

In said drawings:—

Figure 1 is a view showing the invention in side elevation and applied to a window, the latter being shown in section,

Figure 2 is an enlarged longitudinal sectional view through a portion of the invention,

Figure 3 is a view in continuation of Figure 2,

Figure 4 is a cross sectional view taken on the line 4—4 of Figure 3,

Figure 5 is a plan view of the draw cord tensioning means,

Figure 6 is a vertical sectional view taken on the line 6—6 of Figure 5,

Figure 7 is a longitudinal sectional view on the line 7—7 of Figure 1, and

Figure 8 is a sectional detail taken on the line 8—8 of Figure 2.

Referring specifically to the drawings, a vertically slidable window sash is shown at 10, which may be the lower sash of a pair according to the usual construction.

In carrying out the invention, an attaching and bearing section is provided at 11 which has a lug 12 adapted to engage one side of the window sash 10 and which has a screw

clamp 13 threaded in a lug 14 on the bearing and adapted to engage the other side of the sash. The bearing 11 is thus located between the lower portion of the sash and the sill 15 and with the parts attached, the sash 10 is practically closed.

An operating tube 16 is slidable and rotatable in the bearing 11 and at one end thereof has a casing 17 screw threaded thereto as at 18. The casing is preferably in detachable sections as shown connected together by bolts or screws as at 19.

An operating electric motor is shown at 20 which is carried by a bracket or clamp 21 secured to the rod 16. Such motor receives electric current from any suitable source of supply through conductors 22 which pass through a manipulating handle 23 provided on the casing 17. Said conductors 22 may extend from an attaching plug 24 and intermediate their length have a cut off switch 25, suitably located in the casing and operable through the manipulation of a lever 26.

Said electric motor 20 has a shaft 27 journaled transversely of the casing 17 on which a pinion 28 is keyed. Said pinion 28 is in mesh with a larger pinion or gear wheel 29 keyed to a shaft 30 also journaled transversely of the casing 17 and to which a flexible brush-operating shaft 31 is connected so as to be operable thereby.

Said tube 16 at the forward end is provided with a returned portion or crook 32 and a tubular section 33 is pivoted thereto at 34. The tubular section 33 includes a tube 35, a flexible tube 35' bridging the tube 35 and the crook 32. A flexible tube 36 extends from tube 35 to a bearing 37. Said bearing 37 is pivoted at 38 to a bracket 39 clamped or otherwise fastened as at 40 to the tube 35.

The flexible shaft 31 extends through all of the tubes described and within the bearing 37 is fastened to a rotatable stub shaft 41 operable against ball bearings 42. The stub shaft 41 has a brush or washing element 43 detachably connected thereto as by means of a socket member 44. The outer end of stub shaft 41 and socket 44 are square in cross section as shown in Figure 4 and they are normally held attached by a ball clutch 45.

engaging a recess 46 in the socket member 44 and urged to that position by an expansive spring 47. This construction permits the brush to be readily attached or detached as desired.

A leaf spring is provided at 48 having one end at 49 welded or otherwise fastened to the crook 32. This spring at the free end 50 exerts pressure against the tubular section 33, 10 thus urging that section upwardly and outwardly away from the window sash 10. Connected to the spring 48 is a block 51 mounting a housing 52. A shaft 53 is journaled in the housing and has a coil spring 54 secured thereto to which a flexible element or cord 55 is attached which is guided over a pulley 56 carried by a bracket 57 secured by a screw 58 to the bearing 11, and which cord at the opposite end is fastened in an eye 59 of the 20 arm 39. Shaft 53 may be operated by a knob 60 and it may carry a ratchet member 61 with which a spring pressed pawl 62 coacts. Through the turning of the shaft 53, the tension of the spring 54 may be regulated since 25 the pawl 62 will operate automatically to hold the shaft at different adjustments.

It will be realized that with the device installed as shown in Figure 1, and the motor 20 in operation with the operator engaging 30 the handle 23, that the parts may be moved in and out or reciprocated whereby the cord 55 and spring 48, cause the brush 43 to move up and down, with the parts yielding as previously described to enable the brush to follow the window. At the same time, the handle 23 may be turned to thus turn the shaft or tube 16 and brush as a further aid in touching all portions of the window. The brush, it will be realized rotates and before 40 it is applied to the glass or window pane, is moistened and provided with a cleaning or cleansing medium. In order to gain access to the corners of the window, the device may be sufficiently operated to reach them 45 when the current of the motor 20 is cut off.

It will also be realized that if desired, where electric current is not available, the shaft 30 may appropriately be operated or rotated manually.

50 Various changes may be resorted to provided they fall within the spirit and scope of the invention.

I claim as my invention:—

1. A window washer of the class described, 55 comprising an attaching bearing, a tubular member slidable and rotatable in said bearing, a tubular section pivoted to said tubular member, a brush carried by said tubular section, a flexible element connected to said tubular section adjacent to its free end and to the tubular member adjacent to the pivoted connection with said section, means on said bearing for guiding the flexible element, said flexible element adapted to move the tubular section in one direction by sliding movement 60

of the tubular member, spring means on said member and engaging said tubular section to move it in the opposite direction, and a flexible shaft in the tubular member and section to operate the brush. 70

2. A window washer of the class described, comprising an attaching bearing, a tubular member slidable and rotatable in said bearing, a tubular section pivoted to said tubular member, a brush carried by said tubular section, a flexible element connected to said tubular section, adjacent to its free end and to the tubular member adjacent to the pivoted connection with said section, means on said bearing for guiding the flexible element, said flexible element adapted to move the tubular section in one direction by sliding movement of the tubular member, spring means on said member and engaging said tubular section to move it in the opposite direction, means operable through the tubular member and section to operate the brush comprising a flexible shaft, and means mounted on the tubular member to rotate the shaft. 80

3. A window washer of the class described, comprising an attaching bearing, a tubular member slidable and rotatable in said bearing, a tubular section pivoted to said tubular member, a brush carried by said tubular section, a flexible element connected to said tubular section adjacent to its free end and to the tubular member adjacent to the pivoted connection with said section, means on said bearing for guiding the flexible element, said flexible element adapted to move the tubular section in one direction by sliding movement of the tubular member, spring means on said member and engaging said tubular section to move it in the opposite direction, means operable through the tubular member and section to operate the brush comprising a flexible shaft, means mounted on the tubular member operable to rotate the shaft, comprising an electric motor, a casing on the tubular member, gearing in said casing driven by the motor and in driving relation with the flexible shaft, a handle on said casing, and conductor means for the electric motor passing through said handle. 100

4. A washing device of the class described, comprising a tubular member, a bearing for said tubular member, a tubular section pivoted to said member, a flexible shaft operable in said tubular member and section, a spring secured to the member and engaging the tubular section to urge it in one direction, a flexible means connecting the tubular section adjacent to its free end and the tubular member adjacent to the pivoted connection with said section, means on said bearing for guiding the flexible element, said spring and flexible means being adapted to move the tubular section in opposite directions through sliding movement of the tubular member in the bearing, a bearing member pivoted on said tubu- 115 120 125 130

lar section, a stub shaft journaled in said bearing member and operatively connected to said flexible shaft, and a brush carried by said stub shaft.

5 5. A washing device of the class described, comprising a tubular member, a bearing for said tubular member, a tubular section pivoted to said member, a flexible shaft operable in said tubular member and section, a spring 10 secured to the member and engaging the tubular section to urge it in one direction, a flexible means connecting the tubular section adjacent to its free end and the tubular member adjacent to the pivoted connection with 15 said section, means on said bearing for guiding the flexible element, said spring and flexible means being adapted to move the tubular section in opposite directions through sliding movement of the tubular member in the bearing, a bearing member pivoted on said tubular section, a stub shaft journaled in said bearing member and operatively connected to 20 said flexible shaft, a brush carried by said stub shaft, and means operable to tension said 25 flexible means.

6. A washing device of the class described, comprising a tubular member, a bearing for said tubular member, a tubular section pivoted to said member, a flexible shaft operable 30 in said tubular member and section, a spring secured to the member and engaging the tubular section to urge it in one direction, a flexible means connecting the tubular section adjacent to its free end and the tubular member adjacent to the pivoted connection with 35 said section, means on said bearing for guiding the flexible element, said spring and flexible means being adapted to move the tubular section in opposite directions through sliding 40 movement of the tubular member in the bearing, a bearing member pivoted on said tubular section, a stub shaft journaled in said bearing member and operatively connected to said flexible shaft, a brush carried by said stub 45 shaft, means operable to tension said flexible means, comprising a spring secured to said flexible means at one of its ends, a shaft to which the other end of said spring is secured, a ratchet on the shaft, and a pawl coacting 50 with the ratchet.

In testimony whereof I affix my signature.
DARRELL F. WOLF.
